CONTAINER SHIP CRANES

This invention relates to a ship crane used to load and unload containers to and from said ship. It is particularly useful in providing a relatively inexpensive and compact means of loading and unloading containers into and out of a ship from either or both side thereof.

Container ship cranes are broadly old and well known. They have heretofore existed in several forms. One form consisted of a gantry having rotatable arms capable of swinging the arms to overhang the ship deck or the dock. Such cranes were however expensive to build and operate, and were too balky and restricted in movement to operate in certain dock areas and to load and unload certain ships or portions thereof.

Another form, as shown in Myers et al., U.S. Pat. No. 3,130,840, consisted of a lifting trolley and a counterbalancing machinery trolley adapted to be carried on rails by extensible girders over the ship deck and either side of the ship, which extensible girders was in turn carried by C-shaped supports above the ship deck on spaced apart parallel trackways positioned lengthwise of the ship adjacent each side of the ship. Such crane device was relatively compact and could be operated over almost any cargo area and deck area, but was commercially limited because it was expensive to build and maintain.

Still another form, as shown for example in Anderson, U.S. Pat. No. 2,490,609, consisted of a hoist means adapted to be carried by rails or rolls by a single extensible girder over the ship deck and either side of the ship, which extensible girder was in turn carried beneath a main girder on rolls. The main girder was in turn supported by A-shaped supports above the ship deck on spaced apart parallel trackways positioned lengthwise of the ship adjacent each side of the ship. Such crane device was relatively compact and could be operated over almost any cargo area and deck area, but was commercially limited because it was relatively complex to build and maintain. For example, the drive means for the extensible girder had to have the power means mounted on the main girder on the ship deck and complex reeving and sheaves, because of the need for free movement of hoist means along the extensible girder from one extreme position where the extensible girder and hoist means extend over one side of the ship to an opposite extreme position where the extensible girder and hoist means extend over the opposite of the ship.

The present invention overcomes these difficulties and disadvantages, and provides a compact container ship crane which is relatively inexpensive to build and maintain.

I provide a container ship crane movable on spaced apart trackways adjacent each edge of a ship deck and substantially parallel to the centerline of the ship. A single main girder is extended transverse of the ship deck. Leg means support said main girder, preferably at end portions vertically above the ship deck and adapted to move on the trackways on the ship deck. Drive means power said leg means along the trackways. An extensible single girder is movably mounted on and side by side with said main girder for moving substantially transverse to the centerline of the ship from one extreme position where the extensible girder extends over one side of the ship to an opposite extreme position where the extensible girder extends over the opposite side of the ship. Hoist means is movably mounted on said extensible girder for moving from one end of the extensible girder to the other end.

Said extensible girder is mounted on said main girder and guided along said main girder by support means positioned adjacent each end portion of said extensible girder and intermediate said end portions of said extensible girder each support means and adapted to extend across top portions and down side portions of said main girder.

I prefer that the support means intermediate said end portions of said extensible girder be positioned substantially at the center of said extensible girder and that it provide the main support for said extensible girder.

First power means is provided for moving said extensible girder along said main girder which is attached to said main girder possibly through intermediate supports and engages said main girder. Preferably said first drive means is mounted on the support means positioned intermediate the end portions of the extensible girder. Second drive means is provided for moving said hoist means along said extensible girder. Preferably said first and second drive means is a single drive means for moving said extensible girder along said main girder and for moving said hoist means.

Other details, objects, and advantages of my invention will become apparent as the following description of the presently preferred embodiments proceed.

In the accompanying drawings I illustrate presently preferred embodiments of my invention in which:

FIG. 1 is a side view of a ship showing two married container ship cranes according to my invention over each hole of the ship;

FIG. 2 is a top view of the deck of FIG. 1 showing two married container ship cranes according to my invention over each hole of the ship;

FIG. 3 is an enlarged end view of two married container ship cranes according to my invention;

FIG. 4 is an enlarged partial side view of a container ship crane according to my invention; and

FIG. 5 is an enlarged partial top view of a container ship crane according to my invention.

Referring specifically to the drawings, there is illustrated a ship 10 having a deck 11, a forward hold 12 and a rearward hold 13. Above the forward hold 12 and the rearward hold 13 there are provided two married container ship cranes 14 according to my invention, wherein each married container ship crane 14 is movable on spaced apart trackways 15 adjacent each edge 16 of the deck 11 and substantially parallel to the centerline 17 of the ship 10.

Each container ship crane 14 has a single main girder 18 extending transversely of the deck 11. Said main girder 18 is supported by leg means 19, each of an inverted substantially T-shape, vertically above the deck 11 which is provided with wheels 20 for movement on the trackways 15 on the deck 11. One of said wheels 20 is driven by conventional drive means 21 for moving the container ship crane 14 along the trackways 15.

An extensible single girder 22 is movably mounted on and side by side with said main girder 18 for movement substantially transverse to the centerline of the ship 10 from one extreme position where said extensible girder 22 extends over one side of the ship 10 to an opposite extreme position where said extensible girder 22 extends over the opposite side of the ship 10. Said extensible girder 22 is carried on said main girder 18 by a driving means 23 and support means 34 and 34' positioned adjacent and intermediate end portions of extensible girder 22 respectively.

Said driving means 23 is rigidly fastened to said extensible girder 22 substantially at the centerline thereof through support means 34, said support means 34' being carried by wheel means 24 on rail 25, said rail 25 being fixed along said main girder 18. Said support means 34' is guided along said main girder 18 by wheel means 26, 27 and 28 which engage trackways 29, 30 and 31 respectively, said trackways being fixed along said main girder 18. Said driving means 23 carries a motor 32 and a gear assembly 33 adapted to move along

rack 58 on main girder 18, and thereby move said extensible girder 22 along said main girder 18. Said motor 32 is powered through a power track 59. Said motor 32 and gear assembly are positioned on said support means 34' so that the weight of the extensible girder 22 is counterbalanced over wheel 24.

Said support means 34 are rigidly fastened to each end portion of extensible girder 22 and are provided with wheels 35, 36 and 36a that are adapted to engage trackways 29, 30 and 31 respectively. By this arrangement, one of the support means 34 is in contact with the main girder 18 at all times to provide support for said extensible girder 22.

Hoist means 37 is movably mounted on said extensible girder 22 for movement substantially transverse to the centerline of the ship 10 from one end portion of said extensible girder 22 to the opposite end portions of said extensible girder 22. Said hoist means 37 carries a cab 60, a drive motor 38, gear assembly 39, and drums 40, for hoisting a lift beam 41 on cables 42. Said hoist means 37 is powered through power track 61. Said hoist means 37 is carried by wheels 43, 44 and 45 that engage rail 46, said rail being fixed along said extensible girder 22. And said hoist means 37 is guided along said extensible means 22 by wheel 47 which engages trackway 48.

Said hoist means is moved along the extensible girder 22 by means of travel rope reeving 49. Travel rope reeving 49 consists of sheaves 50 positioned at one end portion of said extensible girder 22 and sheaves 51 positioned at opposite end portions of said extensible girder 22. Travel cable 52, is dead ended on hoist means 37 at 53, passes around sheaves 50, and is dead ended on said main girder 18 at its center portion 54. Travel cable 55 is dead ended on hoist means 37 at 56, passes through sheaves 51, and is dead ended on said main girder 18 at center portions 57. By this arrangement the hoist means 37 is moved along said extensible girder 22 in unison with the movement of said extensible girder 22 along said main girder 18 from one extreme position where said extensible girder 22 and the hoist means 37 extend over one side of the ship 10 to an opposite extreme position where said extensible girder 22 and the hoist means 37 extend over the opposite side of the ship 10. No separate power means is needed to move hoist means 37 along said extensible girder 22. As shown in FIG. 3, two ship container cranes 14 can be married at 62 and operated in unison.

The ship container crane 14 is operated as follows. The driving means 23 is energized to move the wheels 20 and in turn the container ship crane 14 to the desired position on the ship 10 to load or unload containers. In the case of loading from the dock, the motor 32 is energized to drive the gear assembly 33 along rack 58 and thereby run out said extensible girder 22 on wheel 24 over rail 25, and said hoist means 37 on wheels 43, 44 and 45 over rail 46, until said extensible girder 22 and said hoist means 37 are positioned over the container to be loaded. The drive motor 38 is then energized to drive drums 40 and thereby lower lift beam 41 on cables 42. After the container is attached to the lift beam 41, the drive motor 38 is again energized to lift the lift beam 41 and the container until it will clear the deck 11 and any obstacles thereon. The motor 32 is then energized to move said extensible girder 22 along said main girder 18, and said hoist means 37 along said extensible girder 22, until the lift beam 41 and the container thereon is positioned over the desired hatch in either the forward hold 12 or the rearward hold 13. Drive motor 38 is then energized to lower the lift beam 41 and the container on cables 42 through the hatch into the hold 12 or 13 to the desired location, where the container is detached from the lift beam 41. In the case of unloading from the ship 10, the operation is the reverse of that just described.

While I have illustrated and described certain present

preferred embodiments of my invention, it is to be understood that I do not limit myself thereto that my invention may be otherwise variously practiced within the scope of the following claims.

5 I claim:

1. A container ship crane movable on spaced apart trackways adjacent each edge of a ship deck and substantially parallel to the centerline of the ship comprising: a single main girder extending transverse of the ship deck; leg means 10 movably mounted on the trackways of the ship deck for supporting said main girder vertically above the ship deck; drive means for driving said leg means along the trackways; an extensible single girder movably positioned substantially side by side with said main girder for movement substantially transverse to the centerline of the ship from one extreme position where the extensible girder extends over one side of the ship to an opposite extreme position where the extensible girder extends over the opposite side of the ship; support means for mounting said extensible girder on said main girder and guiding said extensible girder along said main girder positioned adjacent and intermediate end portions of said extensible girder, and adapted to extend across top portions and down side portions of said main girder; hoist means movably mounted on said extensible girder for movement substantially transverse to the centerline of the ship from one end portion of said extensible girder; first drive means for moving said extensible girder along said main girder attached to said extensible girder possibly through intermediate supports and engage said main girder; and second drive means for moving said hoist means along said extensible girder.
2. A container ship crane as claimed in claim 1 wherein: said leg means are in inverted substantially T-shape and each said leg means is attached to an end portion of said main girder.
3. A container ship crane as claimed in claim 1 wherein: said support means positioned intermediate said end portions of said extensible girder is positioned substantially at the center of said extensible girder and has said first drive means mounted thereon.
4. A container ship crane as claimed in claim 1 wherein: said first and second drive means is a single drive means for moving said extensible girder along said main girder and for moving said hoist means along said extensible girder in unison, from one extreme position where said extensible and said hoist means extend over one side of the ship to an opposite extreme position where said extensible girder and said hoist means extend over the opposite side of the ship.
5. A container ship crane as claimed in claim 4 comprising in addition: sheaves positioned at each end portion of said extensible girder; and cables, each said cable passing through the sheaves at one end portion of said extensible girder and dead ending on the hoist means and on the main girder at its center portion.
6. A container ship crane as claimed in claim 1 wherein: said first drive means is mounted on said support means positioned intermediate said end portions of said extensible girder.
